UNITED STATES PATENT OFFICE.

NEWTON W. BUCH, OF NEW CASTLE, PENNSYLVANIA, ASSIGNOR TO SAFETY ARMORITE CONDUIT COMPANY, OF PITTSBURGH, PENNSYLVANIA, A CORPORATION OF PENNSYLVANIA.

METHOD OF GALVANIZING PIPE.

1,184,315.

Specification of Letters Patent. Patented May 23, 1916.

Application filed June 23, 1913, Serial No. 775,249. Renewed December 19, 1914. Serial No. 878,186.

To all whom it may concern:

Be it known that I, NEWTON W. BUCH, a citizen of the United States, residing at New Castle, Lawrence county, Pennsylvania, have invented a new and useful Improvement in the Method of Galvanizing Pipe, of which the following is a full, clear, and exact description, reference being had to the accompanying drawings, forming part 10 of this specification, in which—

Figure 1 is a longitudinal section of one form of apparatus which may be employed in carrying out my invention; Fig. 2 is a plan view of the same; and Fig. 3 is a section 15 on the line III—III of Fig. 1.

My invention relates to the treatment of pipes, and is designed to provide a continuous method of novel character by means of which the work of galvanizing may be 20 rapidly and thoroughly performed.

In carrying out my invention, I provide a suitable tank or vessel 2, which contains the bath of hot galvanizing material, and which is provided at its ends with suitable guide 25 rollers 3, over and between which the pipes to be galvanized are passed in entering and leaving the tank. One of the rolls 3 at the leaving end of the tank is positively driven by any suitable means such as the pulley 4.

The pipes 5 to be galvanized are first 30 provided with threaded ends and successive lengths of the pipe are united by couplings.

The tank or vessel 2 is of sufficient 35 length to receive a great enough length of pipe or coupled pipes between the guide rollers to permit of the deflection of the central portion of the pipe below the surface of the molten bath. This deflection can be effected in part by gravity, and partly by the

use of a centrally arranged depressing wheel 40 or roller 7. In some cases this roller may be dispensed with, as the weight of the pipe alone will be sufficient to cause the central portion to be sufficiently deflected into the

45 bath. The operation is a continuous one, successive sections being removed at the delivery end of the tank, and other sections being successively coupled on at the entrance end. I preferably provide a wiping brush

50 near the delivery end of the tank for the purpose of removing excess coating material. This device is shown as in the form of a hollow rotary brush 8, which is revolved about the pipe by any suitable means such 55 as the drive chain illustrated at 9.

The advantages of my invention will be apparent to those skilled in the art, since it provides an extremely efficient and rapid method of galvanizing pipes.

The invention also overcomes the difficulty 60 which has heretofore been experienced due to the rapid vaporization within the pipe of any moisture such as remains of the vapor acid bath to which the pipes have been previously subjected. It will be noted that the 65 ends of the connecting pipes passing through the bath are open to permit the free escape of steam and a vapor at points outside the bath. It will further be noted that my invention provides means whereby the pipe 70 couplings may be galvanized simultaneously with the pipes. A further advantage consists in the fact that the threaded ends of the pipe are largely protected against being coated, and that no galvanizing material can 75 enter the interior of the pipes or couplings during the galvanizing operation.

It will be understood that any suitable arrangement of apparatus other than that illustrated may be employed in carrying out 80 my improved method. Thus, any suitable form of tank may be employed; the pipes may be fed through the bath by any suitable means; and the tank may be arranged so that a number of connected lengths of 85 pipe may be simultaneously passed therethrough side by side.

While I have shown my invention as being carried out in connection with hot-galvanizing, it will be readily understood that 90 my improved method is also applicable to electro-galvanizing, the pipes being connected and moved through the electrolyte in a manner similar to that to hot-galvanizing. The invention is also applicable to 95 galvanizing rods as well as pipes, and by the term "pipes" as used in the appended claims I intend to cover the galvanizing of successive lengths, either solid or hollow, 100 when connected together in the manner described. While the invention is more particularly designed for coating such articles with zinc, it is obvious that it may be employed for coating with other materials.

I, claim:—

1. The herein described method of coating rods or pipes having threaded ends, which consists in connecting successive pipe or rod sections together by means of couplings which inclose and protect the threads,

- and passing such connected sections continuously through a coating bath and disconnecting the coated sections after they leave the bath, substantially as described.
2. The herein described method of coating the exterior surfaces only of hollow pipes, which consists in connecting the pipes to be coated end to end by means of suitable temporary couplings which will prevent access of the coating material to the interior of the pipes, passing the connecting pipes through a coating bath in a longitudinal direction, and disconnecting the successive lengths of the coated pipe as they leave the bath and adding successive lengths of uncoated pipe at the opposite end, substantially as described.
3. The herein described method of coat-

ing the exterior surface only of hollow pipes having threaded ends, which consists in connecting the pipes by couplings engaging said threaded ends and of a character to prevent the coating material from reaching the threads and also the interior of the pipes, passing the connected pipes through a coating bath in a longitudinal direction, and disconnecting the successive lengths of the coated pipe after they leave the bath, substantially as described.

In testimony whereof, I have hereunto set my hand.

NEWTON W. BUCH.
